CENTERLESS GRINDING OF LONGITUDINALLY CONTOURED ARTICLES

Raymond H. Cramer, Bloomfield, N. J., assignor to General Motors Corporation, Detroit, Mich., a corporation of Delaware

Application July 17, 1947, Serial No. 761,694

23 Claims. (Cl. 51—74)

1

This invention relates to centerless grinding of longitudinally contoured articles, especially bearing rollers of the barrel or the waisted types. An object of the invention is to provide a machine of the general type shown in my Patent 2,156,562 but capable of faster operation and greater production. In that prior machine barrel shaped rollers are traversed in one direction across a concave grinding wheel while supported by a work rest and a regulating wheel which oscillate as a unit around an axis, a feeding mechanism inserting a roller onto the rest from one side of the grinding wheel at the beginning of a stroke and an ejector removing the roller at the end of the stroke, the return stroke being idle. It has been proposed to grind rollers in both directions of oscillation but such proposals have required two feeding mechanisms and two ejecting mechanisms. Another object of the invention is to provide a machine of this general character which will grind rollers in both directions of oscillation with the employment of a single feeding and ejecting mechanism capable of fast and reliable operation. In general this object is accomplished by mounting a combined feeding and ejecting mechanism on the oscillating unit itself for actuation thereby, guiding a column of rollers downwardly between the wheels onto the work rest, and making the regulating wheel narrower than the length of the rollers so that ejecting fingers alongside the regulating wheel will eject a finished roller and cause the quick application of a new roller to grinding position at the end of every stroke of oscillation.

To these ends and also to improve generally upon apparatus of this character, the invention consists in the various matters hereinafter described and claimed. In its broader aspects, the invention is not necessarily limited to the specific construction selected for illustrative purposes in the accompanying drawings in which

Fig. 1 is a front elevation of the oscillating unit as seen from grinding wheel side of the work rest.

Fig. 2 is a side elevation of Fig. 1, the position of the two wheels being additionally indicated.

Fig. 3 is a plan view of Fig. 2, the extent of oscillation of the oscillating unit being indicated by two broken line showings of the grinding wheel.

Fig. 4 is an exploded perspective view of four parts of the feed mechanism near the top of the oscillating unit.

Fig. 5 is an enlarged vertical section through

2

the grinding wheel and the work chute with other elements in side elevation.

Fig. 6 is a horizontal section of Fig. 5 just above the work being ground.

Fig. 7 is a perspective view of certain feeding and ejecting elements.

Fig. 8 is an exploded perspective view, parts being in section, of a work chute and associated parts.

Fig. 9 is a horizontal sectional view of a supporting post, the section being taken just above the top of the work rest.

Fig. 10 is an exploded perspective view of a portion of the supporting post and certain clamping members for the work guides and the work rest.

Fig. 11 is a perspective view of the supporting post.

Fig. 12 is an exploded perspective view of a reciprocating cam and its guide.

Fig. 13 is a plan view of a work rest and guide plates.

Fig. 14 is a front view of Fig. 13.

The work piece W to be ground, herein shown as a barrel shaped roller, is supported on a blade or work rest S and a narrow regulating wheel R which oscillate as a unit to traverse the work endwise along the concave periphery of a wide grinding wheel G. A feeding and ejecting mechanism is also mounted on the oscillating unit and a finished roller is ejected and a new roller is lowered onto the work rest at the end of each stroke of oscillation.

The rollers are urged endwise by a suitable feeder through a flexible feed tube 2 whose lower end is supported in a bushing fastened by a set screw in an opening 4 of a bracket 6. The top of the bracket has a channel open upwardly to receive a horizontal roller guide 8 which is secured by two screws engaging two washers 10, the latter being set into complementary recesses 12 and 14 in the roller guide and in the bracket respectively. The roller guide has a side opening 16 registering with the feed tube 2 to receive the rollers therefrom, this opening extending into a longitudinal guideway 18 at the top of the roller guide. The bottom of the roller guide has an exit opening which conducts each roller downwardly into a work chute 22 after the roller has been pushed sidewise along the guide over the opening by an in-feed finger 24 on a rockable transfer arm 26.

Fastened by screws in adjusted position in the bottom of the guideway 18 is a rectangular back stop 30 having slots for the screws. The back

stop has a front stop face which terminates at the rear of the bottom opening in the roller guide. The back stop has a tapped opening for a vertical screw 34 which extends upwardly through a slot in a cover plate 36, a coil spring 38 being interposed between the cover plate and a nut at the top of the screw. The cover plate presses downwardly on the rollers and prevents their upward movement as they are pushed along the channel of the roller guide to the stop surface.

The chute 22 (Fig. 8) has two drilled openings 42 for screws which fasten the chute in a nearly vertical position on a web which connects the two upright legs of the bracket 6. The chute body is of U-shaped cross section with parallel end walls 43 and a bottom or side wall 44 which extends downwardly from the roller guide into a close proximity to the regulating wheel, the lower end of the side wall having an arcuate surface which extends into a sharp projection 46 which just clears the regulating wheel. The center line of the work chute is in the central plane of the regulating wheel. The chute has tapped openings 48 for screws which pass through drilled openings 50 of an upper cover plate 52, the cover plate having central elongated slots 54 to render the rollers visible. Two other screws similarly secure a lower cover plate 56 to the chute body, the lower cover plate having a slot 58 and a sharply pointed extension 60 which is also slit and extends into very close proximity to the grinding wheel. The upper and lower cover plates constitute a front side wall opposite to the rear side wall 44, and the lower cover plate extends downwardly farther than the side wall 44 and close to the work rest to co-operate with the regulating wheel in guiding a column of rollers onto the work rest S.

As the rollers leave the end walls 43 and approach the work rest, their ends are guided between the adjacent parallel edges of an upper pair of arcuate clamping plates 66 which are fastened by screws in the upper portions of arcuate recesses 68 in an upright supporting post 70. Each clamping plate has a bevelled lower surface which overlaps a similar bevel on a work locating and guiding plate 72 to hold the latter against the post. A similar lower pair of arcuate clamping plates 74 have their upper surfaces bevelled to overlap and clamp similar bevels at the lower edges of the plates 72. The plates 72 have a portion of their adjacent edges 76 arranged to converge downwardly to guide and center the rollers as they enter between parallel locating surfaces 78 which locate each roller endwise while supported on the work rest.

The work rest which has parallel vertical edges 80 and bevelled sides 82 is fastened by a clamp 84 in a vertical recess 86 at the front of the post, one side of the recess being undercut. The top of the work rest is very slightly longer than the rollers which are first end ground to very close tolerances. Then, when the lower portions of the parallel locating surfaces 78 are brought up against the vertical edges 80 of the work rest and clamped there, each roller is free to rotate but can have no appreciable endwise movement in either direction. The top of the work rest slants downwardly towards the regulating wheel but longitudinally it is curved to conform to the roller. The post has a base flange 88 fastened by screws to the top of an oscillating head 90. The top of the post has horizontal rabbeted rails 92 on which are fastened similar rails at the bottom of the bracket 6. The middle portion of the

post has a deep central recess 93 above which the post is divided so that the regulating wheel can approach closely to the work rest. The regulating wheel may conveniently be supported on the oscillating unit and driven by mechanism similar to that disclosed in Figs. 1 and 2 of my above cited Patent 2,156,562.

The transfer arm 26 is in the form of a yoke whose opposite arms straddle the chute 22. The lower ends of the opposite arms are connected (Fig. 7) by a web 94 behind the chute and the ends project downwardly beyond the web to form bearing hubs 96 which are split and clamped by screws to a rock shaft 98. The rock shaft is journalled in bushings in bearing bosses 100 on the spaced legs of the bracket 6. An anchor screw threaded in the web 94 is connected by a tension spring 102 to an adjusting screw 104 having a threaded adjusting knob 106 bearing on a rounded aligning washer 108 which engages a cross plate 110 fastened on the bracket 6. The split hub portion 112 of an ejector arm 114 is clamped on the rock shaft between the bearing hubs 96. The ejector arm has riveted thereto a pair of parallel, 25 spring steel extensions 116 which straddle the narrow regulating wheel and terminate in bent tips or ejecting fingers 118 which can be projected between the work rest and the cover plate extension 60 to eject a finished roller at one side of the grinding wheel when the oscillating unit is at either end of its stroke. The regulating wheel is narrower than the length of the work pieces so that the ejecting fingers can also pass between the guiding plates 72 as they engage the work piece near the ends.

The rock shaft 98 is cam actuated under control of the oscillating stroke. A cam engaging arm or follower 120 has a split hub clamped to one end of the rock shaft and extending upwardly. The arm has a pointed tip adapted to be actuated by a V-shaped cam recess in a cam plate 122 fastened in a recess of a vertically reciprocating cam bar 124. The cam bar is guided in a vertically elongated box or guide (Figs. 1, 3 and 12) comprising a body 126 of U-shaped cross section and a connected cover 128, the guiding unit being fastened to one side of the bracket 6. Holding pins 130 project inwardly of the guide into openings of hardened guiding plates or inserts 132 and 134. Holding pins also project inwardly from the cover 128 to support a hardened insert 136 which occupies a groove 138 in the cover. The hardened insert 136 has a rectangular opening for a strong leaf spring 140 interposed between the cover and the cam bar 124 to hold the latter in its elevated or depressed position. A portion of the guide body 126 is cut out at 142 and a portion of the cover is similarly cut out at 144 to let the cam plate 122 reciprocate and engage the cam follower 120.

The lower end of the cam bar 124 has a horizontal projection 146 which is rigidly connected to a horizontal projection 148 on the upper end of an actuating link 150, the connection comprising a key 152 engaging grooves in the two projections with a holding screw 153 passing through a slot in the extension 148 into a tapped hole in the extension 146. The cam bar 124 and the actuating link 150 are thus in effect a single member. The lower portion of the link is laterally curved or offset and its lower end has a projecting cross pin 154 engaging slots in a forked arm 156 of a bell crank lever which is journalled for rocking movement on a bushing carried by a shouldered stud 158 which is threaded in a plate

160 fastened on the arcuate exterior of the oscillating head 90. A vertical depending arm 162 of the bell crank lever is adapted to engage alternately with abutment screws 164 and 166 each clamped by a nut in adjusted position on a lug of a stop bracket 168 fastened in a fixed position on the fixed base 170 of the machine. The two abutment screws are spaced apart about 120° and the oscillating head causes the opposite sides of the arm 162 to alternately engage the screws to actuate the rock shaft 98 and the feeding and ejecting mechanism. Fig. 3 indicates the amplitude of oscillation by two broken line showings of the grinding wheel but it will be understood that the grinding wheel remains in its own plane and that all other parts oscillate except the base and the abutment screws with their supporting brackets.

The cam and cam bar are shown in an intermediate and transitory position in Fig. 2 with the point of the cam follower 120 pulled into the V-shaped recess of the cam plate 122. In this position, the ejecting fingers 118 have been projected over the work rest to eject a finished roller at one side of the grinding wheel while the in-feed finger 24 has been advanced into the work guide to move a roller sidewise over the entrance to the chute 22. This is the position of the parts only at the instant of reversal of the stroke and the cam immediately continues its upward or downward stroke to retract the ejecting fingers and the in-feed finger. The last roller in the chute then drops from the fingers 118 onto the work rest. During actual grinding the cam follower 120 rests on the straight part of the cam either above or below the V-shaped recess. The cam bar is held in its upper or its lower position by the friction of the leaf spring 140 until the bell crank arm 162 engages one of the abutment screws. Then the cam is given its entire stroke for the momentary actuation of the ejecting and transfer members both forward and back to retracted positions.

In practice, the chute contains a plurality or column of rollers each supporting the next one above it so that the roller next above the one being ground has only a short distance to fall in order to replace a finished roller. Several rollers are manually fed into the chute initially to form the column which is then maintained because of the infeed of a new roller whenever a finished one is ejected. As a finished roller is ejected, the column of rollers is momentarily supported on the ejecting fingers which are immediately retracted. The space between the slit extension 69 and the work rest is slightly greater than the diameter of a work piece and all work pieces above the one in grinding position are held from contact with the grinding wheel although several rollers will be engaged by the regulating wheel. Every new piece reaching the work rest is immediately rotated due to the rotation of the regulating wheel and the impulse to rotation imparted by withdrawal of the ejecting fingers. In Fig. 6, the clearance between the ends of the roller and the parallel vertical edges of the guiding plates 72 is exaggerated but should be no more than .001 of an inch for satisfactory generation of barrel rollers for roller bearings. The distance between those parallel edges is established by the parallel edges 80 of the work rest.

I claim:

1. In a centerless grinding machine having a grinding wheel and an oscillating unit support-

ing a regulating wheel and a work rest, a work feeding mechanism mounted on the oscillating unit to oscillate therewith, said mechanism comprising work guiding means for maintaining a plurality of work pieces substantially aligned with the work rest during said oscillation, and means actuated by oscillation of said unit for removing a ground work piece from the work rest and inserting a new piece thereon from the aligned work guiding means when the work rest and the regulating wheel move beyond the side of the grinding wheel in either direction.

2. In a centerless grinding machine having a grinding wheel and an oscillating unit supporting a regulating wheel and a work rest, a single work feeding mechanism mounted on the oscillating unit, said mechanism comprising a work chute and end guiding plates aligned with the work rest at all times, and means for causing said mechanism to place a new work piece on the work rest at the end of each stroke of the oscillating unit.

3. In a centerless grinding machine having a grinding wheel and an oscillating unit supporting a regulating wheel and a work rest, a work feeding mechanism mounted above the regulating wheel, a reciprocating cam for actuating said mechanism, and means actuated by oscillation of the unit for reciprocating the cam.

4. In a centerless grinding machine having a grinding wheel and an oscillating unit supporting a regulating wheel and a work rest, the wheels being similarly curved crosswise to generate a curvature on interposed work pieces, the unit being mounted to oscillate around an axis to carry the work rest beyond the side of the grinding wheel at each stroke, and means mounted on the oscillating unit and actuated at the end of each stroke for removing a ground work piece from the work rest and supplying a new piece thereto, said means comprising work guides permanently in line with the work rest for holding a plurality of work pieces in peripheral contact, and an ejecting finger oscillated across the work piece.

5. In a centerless grinding machine having a grinding wheel and an oscillating unit supporting a regulating wheel and a work rest, the unit being mounted for oscillation to carry the work rest beyond the side of the grinding wheel at each stroke, the regulating wheel having a width less than the length of the work pieces, work engaging fingers alongside of the regulating wheel and spaced apart a distance less than the length of the work pieces, and means for moving the fingers over the work rest as the oscillating unit approaches the end of its stroke.

6. In a centerless grinding machine having a grinding wheel and an oscillating unit supporting a regulating wheel and a work rest, the unit being mounted for oscillation to carry the work rest beyond the side of the grinding wheel at each stroke, the regulating wheel having a width less than the length of the work pieces, work engaging fingers alongside of the regulating wheel and spaced apart a distance less than the length of the work pieces, a work chute mounted on the oscillating unit and terminating adjacent to the rest, and means for projecting the fingers between the rest and the chute and retracting them near the end of each stroke of the oscillating unit.

7. In a centerless grinding machine having a grinding wheel and an oscillating unit supporting a regulating wheel and a work rest, the regulat-

ing wheel having a width less than the length of the work pieces, work engaging fingers embracing the regulating wheel and spaced apart a distance less than the length of the work pieces, and means for moving said fingers over the work rest to remove a work piece therefrom when the oscillating unit carries the rest beyond the grinding wheel in either direction.

8. In a centerless grinding machine having a grinding wheel and an oscillating unit supporting a regulating wheel and a work rest, a work chute mounted upon the oscillating unit and extending downwardly close to the work rest, the regulating wheel having a width less than the length of the work pieces, and an arm having fingers embracing the regulating wheel and spaced apart a distance less than the length of the work pieces to remove a finished work piece from the rest and lower a new piece from the chute when the oscillating unit moves the rest beyond the side of the grinding wheel in either direction.

9. In a centerless grinding machine having a grinding wheel and an oscillating unit supporting a regulating wheel and a work rest, the unit being mounted for oscillation to carry the work rest beyond the side of the grinding wheel at each stroke, a work chute mounted on the oscillating unit in the plane of the regulating wheel and terminating above the blade, a work ejecting and feeding member movable between the chute and the rest, and means actuated by the oscillating unit at the end of each stroke for reciprocating said member.

10. In a centerless grinding machine having a grinding wheel and an oscillating unit supporting a regulating wheel and a work rest, the unit being mounted for oscillation to carry the work rest beyond the side of the grinding wheel at each stroke, a work chute mounted on the oscillating unit and having side walls adjacent to the wheels, the wall adjacent to the grinding wheel being the longer and coacting with the regulating wheel to guide the work pieces, such longer wall terminating above the work rest at a distance therefrom to form an exit passage for a single work piece only, and means for discharging a finished piece through said passage at each stroke of the oscillating unit.

11. In a grinding machine having a grinding wheel, a regulating wheel, and a work rest, a work chute in the plane of the regulating wheel, the chute having side walls and end walls, the side wall adjacent to the grinding wheel extending downwardly beyond the opposite side wall to coact with the regulating wheel in guiding the work pieces to the work rest, said side wall terminating above the work rest at a distance to form an exit passage for a finished work piece therebetween, and mechanism for expelling a finished work piece through said passage at one side of the grinding wheel.

12. In a centerless grinding machine having a grinding wheel and an oscillating unit supporting a regulating wheel and a work rest, the top of the work rest having a length slightly exceeding the length of the work pieces, work locating plates engaging the ends of the work rest and projecting above it for a distance greater than the diameter of a work piece in order to hold a plurality of contacting work pieces substantially aligned with the work rest, the lower portions of said plates having parallel surfaces to engage the ends of the lowest work piece and limit its endwise movement along the rest when the oscillating unit

traverses the work piece along the grinding wheel in either direction.

13. In a centerless grinding machine having a grinding wheel and an oscillating unit supporting a regulating wheel and a work rest, the top of the work rest having a length slightly exceeding the length of the work pieces, work locating plates engaging the ends of the work rest and projecting above it, said plates having parallel surfaces to engage the ends of the work pieces and limit their endwise movement along the rest when the oscillating unit traverses the work pieces along the grinding wheel, and downwardly converging guide surfaces on said plates to guide the work pieces between the parallel surfaces.

14. In a centerless grinding machine having a grinding wheel and an oscillating unit supporting a regulating wheel and a work rest, the top of the work rest having a length slightly exceeding the length of the work pieces, work locating plates engaging the ends of the work rest and projecting above it, said plates having parallel surfaces to engage the ends of the work pieces and limit their endwise movement along the rest when the oscillating unit traverses the work pieces along the grinding wheel, and a work chute extending downwardly between the wheels to conduct work pieces between said parallel surfaces.

15. In a centerless grinding machine having a grinding wheel and an oscillating unit supporting a regulating wheel and a work rest, a work chute mounted on the oscillating unit and extending downwardly between the wheels to guide a column of work pieces to the work rest, and means for removing a work piece from the rest and supplying a new piece to the rest and another to the chute at each stroke of the oscillating unit.

16. In a centerless grinding machine having a grinding wheel and an oscillating unit supporting a regulating wheel and a work rest, a work chute mounted on the oscillating unit and extending downwardly between the wheels to guide a column of work pieces to the work rest, and means for intermittently lowering the column by the dimension of one piece.

17. In a centerless grinding machine having a grinding wheel and an oscillating unit supporting a regulating wheel and a work rest, a work chute mounted on the oscillating unit and extending downwardly between the wheels to guide a column of work pieces to the work rest, and means for intermittently lowering the column, said means comprising an ejecting member and an infeed member, and a cam actuated by the oscillation of the unit for operating said members.

18. In a centerless grinding machine having a grinding wheel and an oscillating unit supporting a regulating wheel and a work rest, a work chute mounted on the oscillating unit and extending downwardly between the wheels to guide a column of work pieces to the work rest, a finger projectable between the work rest and the chute, and means for reciprocating the finger to remove a finished piece from the work rest and lower the column of rollers to apply a new piece to the work rest.

19. In a centerless grinding machine having a grinding wheel and an oscillating unit supporting a regulating wheel and a work rest, a work chute mounted on the oscillating unit and extending downwardly between the wheels to guide a column of work pieces to the work rest, a work engaging member, a cam shiftably mounted on the oscillating unit to reciprocate said member, means controlled by oscillation of the unit for reciprocating

the cam, and a spring for frictionally holding the cam at each extremity of its movement.

20. In a centerless grinding machine having a grinding wheel and an oscillating unit supporting a regulating wheel and a work rest, a work chute mounted on the oscillating unit and extending downwardly between the wheels to guide a column of work pieces to the work rest, and means for controlling the passage of the work pieces through the chute, said means comprising a cam mounted to reciprocate on the oscillating unit, a spring for frictionally holding the cam at each end of its stroke, a pair of fixed abutments, a movable lever carried by said unit in a position to engage the abutments in alternation, and a connection between the lever and the cam.

21. In a centerless grinding machine having a grinding wheel and an oscillating unit supporting a regulating wheel and a work rest, a bracket mounted on the oscillating unit and extending above the regulating wheel, a work chute mounted on the bracket and extending downwardly towards the work rest, a rock shaft journaled in the bracket, a work engaging arm fixed to the rock shaft, a bar guided by the bracket, a cam and a cam follower, one fixed to the bar and one fixed to the rock shaft, and means for reciprocating the bar as said unit oscillates.

22. In a centerless grinding machine having a grinding wheel and an oscillating unit supporting a regulating wheel and a work rest, a work chute

mounted above the regulating wheel and extending downwardly towards the work rest, and means for intermittently supplying work pieces to the chute, said means comprising a rock shaft, a yoke fixed to the rock shaft and embracing the chute, an in-feed finger attached to the yoke, and a cam reciprocated by the oscillation of said unit for rocking the shaft.

23. In a centerless grinding machine having a grinding wheel and an oscillating unit, a regulating wheel, a work rest, a pair of work locating plates and a work chute all mounted on said unit to oscillate therewith, the work chute being maintained in the plane of the regulating wheel and leading to the work rest, the work locating plates being spaced apart at the ends of the work rest, and means for ejecting a ground roller from the rest and substituting a new roller from the chute at the end of every stroke of oscillation.
